John Rogers.

United States Patent Office.

DESIGN FOR A GROUP OF FIGURES.

JOHN ROGERS, OF NEW YORK, N. Y.

Design No. 2,521, dated December 4, 1866.

SPECIFICATION.

TO ALL WHOM IT MAY CONCERN:

Be it known that I, JOHN ROGERS, of the city of New York, and county and State of New York, have invented or produced a new and original Design for a Group of Figures; and I do hereby declare that the following is a full and exact description of the same.

The group consists of three figures, and is called the Charity Patient. It represents an old doctor, who is interrupted, whilst mixing drugs on the top of a stand of drawers, by a poor woman with a baby in her arms. The doctor has his left hand on the child's head, while the mother watches the doctor's face, anxiously awaiting his decision; all of which can be plainly seen in the accompanying drawings.

What I claim as my invention, and desire to secure by Letters Patent, is—
A design for a group of figures, as shown and described above.

JOHN ROGERS.

Witnesses:

HENRY A. LOOP,
GEO. H. SMILLIE.
